UNITED STATES PATENT OFFICE.

CHARLES H. TALLMAN AND BENJAMIN F. DAY, OF BELLAIRE, OHIO.

TOP OF SIRUP-PITCHERS.

SPECIFICATION forming part of Letters Patent No. 240,562, dated April 26, 1881.

Application filed February 2, 1881. (No model.)

To all whom it may concern:

Be it known that we, CHARLES H. TALLMAN and BENJAMIN F. DAY, of Bellaire, in the county of Belmont and State of Ohio, have 5 invented a new and useful Improvement in Tops of Sirup-Pitchers; and we do hereby declare that the following is a full and exact description of the same, reference being had to the accompanying drawings, and to the letters 10 of reference marked thereon.

The object of the invention is such an improvement in the tops of sirup-pitchers and like articles from which fluids are poured as will effectually cut off the flow when desired 15 and prevent any dripping of the contents after pouring, which top may also be made very cheaply; and our invention therein consists in providing the cover with a spiral spring around the hinge-pin, whereby the cover and its 20 seat act together in cutting off effectually the tendency to drip after pouring from the vessel, and in constructing the same in such a way that it may be made out of scrap metal.

To better understand our invention reference may be had to the accompanying drawings, in which—

Figure 1 is an elevation of one style of cover; Fig. 2, an elevation of another style; Fig. 3, a vertical central section of Fig. 1; Fig. 4, a 30 similar section of Fig. 2.

Like letters denote similar parts in each figure.

The base of the (top denoted by the letter A) is a ring of metal, made out of a narrow 35 strip, soldered at its ends. To this is soldered the nose or seat B for the cover, which is made flaring outwardly, with a portion, a, bent horizontally into a flange, which serves as a support and foundation for the soldering of the 40 parts A and B together. To the top of the part B, at the rear end thereof, is soldered the fixed part C of the cover, having hinge-ears b made upon it. The movable part D of the

cover, having ears c made upon it, is shaped so as to fit closely upon the top of the nose or 45 seat B. The hinge-ears c and b are so arranged as to leave the hinge-pin e in the center, adapted to be covered by a spiral spring, E. A suitable thumb-piece, f, is attached to the top of the cover in any convenient way. 50

In operation, the cover is lifted by pressing upon the thumb-piece, and when this is released the spring forces the cover down upon its seat and holds it there securely, effectually cutting off all drip. 55

In the modification shown in Figs. 2 and 4, which is the cylindrical form, where there is no nose proper; an internal nose is soldered to the flange of the bottom portion, and the seat is soldered upon that, as before described. In 60 this modification the hinge-ears c are soldered to the seat and the ears b directly to the cover.

From this construction it will be apparent that the whole top, being made out of small scraps, may be manufactured very cheaply. 65

Having thus described our invention, what we claim as new therein is—

1. In combination with the top of a sirup-pitcher, a spring coiled around the hinge-pin and acting against the top for the purpose of 70 closing and holding it shut, as set forth.

2. A top for sirup-pitchers having the base-ring A, the nose or seat B, provided with the flange a, the cover D, and ears b b c c, and spring E coiled around the hinge-pin, the several parts constructed and arranged substantially as set forth. 75

This specification signed and witnessed this 31st day of January, 1881.

CHARLES H. TALLMAN.
BENJAMIN F. DAY.
